UNITED STATES PATENT OFFICE.

LAURENCE J. BERKELEY, OF MILWAUKEE, WISCONSIN, ASSIGNOR TO THE P & M COMPANY, OF CHICAGO, ILLINOIS, A CORPORATION OF ILLINOIS.

RAIL ANCHOR.

Application filed April 20, 1921. Serial No. 462,848.

To all whom it may concern:

Be it known that I, LAURENCE J. BERKELEY, a citizen of the United States, residing at Milwaukee, in the county of Milwaukee and State of Wisconsin, have invented certain new and useful Improvements in Rail Anchors, of which the following is a specification.

My invention relates to devices for resisting the longitudinal creeping movement of railroad rails, and has for its primary object the provision of a new and improved device of this character which will be of simple construction, inexpensive to manufacture, easy of application to a rail, and which will maintain a firm initial grip on the rail by spring pressure.

A more specific object of my invention is to provide an improved two-piece rail anchor comprising a rigid yoke member, adapted to engage opposite edges of the base of a rail, and a spring member cooperating with the yoke to hold it in operative engagement with the rail and adapted to resist the tendency which the vibration of the rail or other disturbing influences have to loosen the grip of the device on the rail.

A further object of my invention is to provide a rail anchor having a rigid one-piece yoke member formed at one end with a hook-shaped portion adapted to fit over and engage the upper surface of one base flange of a rail and take a pinching grip on the upper and lower surfaces of said base flange, and formed at the other end with a vertically disposed abutment which engages the vertical edge only of the other base flange of the rail; the hook-shaped portion being formed whereby the yoke may be fitted on the rail by fitting the hook-shaped portion over one edge of the rail base and then raising the other end of the yoke to its operative position by rocking the yoke on a horizontal axis longitudinally of the rail.

The invention has for further objects the novel arrangements, constructions and combinations of parts, hereinafter described and claimed, for carrying out the above stated objects, and such other objects as will appear from the following description.

The invention is illustrated in certain preferred embodiments in the accompanying drawings wherein

Fig. 1 is a side elevation of a rail anchor device constructed in accordance with my

invention, the same being shown in full lines in its operative position on a rail, the dotted lines indicating a position of the yoke member of the device while being applied to the rail;

Fig. 2 is a sectional view taken on line 2—2 of Fig. 1, illustrating another position of the parts of the anchor before the anchor is fully applied to the rail.

Fig. 3 is a section taken on line 2—2 of Fig. 1, showing the device in its operative position;

Fig. 4 is a view in elevation of one of the members of my improved rail anchor device;

Fig. 5 is a view in perspective of the yoke member of my device as illustrated in Figs. 1 to 3 inclusive;

Fig. 6 is a plan view of a modified construction showing the device applied to a rail, the rail being indicated in dotted lines; and

Fig. 7 is a view in perspective of the yoke member shown in Fig. 6.

Like characters of reference designate corresponding parts in the several figures of the drawings.

Referring first to Figs. 1 to 5 inclusive of the drawings: 10 designates a yoke member, made preferably of cast metal, formed at one end with a hook-shaped jaw portion 11 adapted to engage the vertical edge 12 and the upper and lower surfaces 13 and 14, respectively, of one of the base flanges of the rail, and formed at the other end with a vertically disposed abutment 15 which engages the vertical edge of the other base flange of the rail. The distance between the vertical portions of the jaw 12 and the abutment 15 is preferably, though not necessarily, substantially the same as the width of the rail base, so that the yoke when applied will stand substantially at right angles to the length of the rail. In order to facilitate the application of the device to a rail, the portion of the yoke defining the lower part of the jaw 11 is inclined downwardly, as indicated at 16, so that the abutment 15 will clear the edge of the rail when the anchor is in the position shown in dotted lines in Fig. 1. The portion of the yoke adjacent the jaw portion 11 is preferably wider than the portion adjacent the jaw 15, and is formed with a depending arm 17 which projects toward the tie 18 and functions as a fulcrum to tilt the yoke to cause the jaw 11

100 to 105 110

to grip the upper and lower surfaces of the rail base. The lower end of the arm is formed with a flat surface 19 providing a seat for a curved spring or key 20 which 5 spring is interposed between the under surface of the rail base and the lower end of the arm.

The spring 20 is strained during its application to its operative position so as to 10 exert pressure against the arm 17 at one side of the longitudinal center of the yoke thereby tilting the yoke in a vertical plane so as to force the edges 21, 22 of the jaw portion 11 into pinching contact with the 15 upper and lower surfaces 13, 14 of the rail base. The tension of the spring 20, in addition to rocking the yoke member so as to effect a pinching grip on the upper and lower surfaces of the base flange, exerts 20 vertical pressure adjacent the edge 12 of the rail base, so as to support the abutment 15 of the yoke in its operative position adjacent the opposite edge of the rail base. The upper edge 23 of the spring 19 preferably 25 inclines downwardly toward the longitudinal center of the rail so that the maximum vertical pressure of the spring will be exerted between the point 24 of the jaw portion 11 and the edge 12 of the rail base. 30 The point 24 of the jaw 11, it will be noted, provides the axis on which the yoke is rocked from the dotted line position (Fig. 1) to its operative position.

A structure of the above character, being adapted to be rocked on a horizontal axis so as to bring the rail-engaging portions of the jaw 11 into gripping contact with the rail base, may be applied to rails having base flanges which differ in thickness or contour, as the clearance between the rail engaging portions of the jaw and the upper and lower surfaces of the rail will be taken up by the rocking movement of the anchor device.

45 In applying the device to a rail, the yoke is passed under the rail base at substantially right angles to the length of the rail, and the hook-shaped jaw 11 fitted over one edge of the rail base, as indicated in dotted 50 lines in Fig. 1. The abutment end 15 of the yoke is then raised until the yoke member assumes the full line position shown in Fig. 1. The spring member 20 is then positioned on the seat 19 of the arm 17 so as 55 to engage with the under surface of the rail base at a point a short distance away from the tie 18, such, for example, as indicated in Fig. 2. The spring member 20 is held in this position and the yoke moved to 60 ward the tie, whereby the spring is tensioned by bending the same to a more pronounced curve. The initial position of the spring is preferably such that the movement of the anchor toward the tie, for example, from the position shown in Fig. 65

2 to the position shown in Fig. 3, will bring the spring member against one of the vertical faces of the tie 18. When the anchor device is in its operative position the upper edge 23 of the spring member abuts 70 against the edge of the yoke member and the outer surface of the spring bears against the tie. When the spring is forced against the tie, for example, by the creeping movement of the rail toward the tie, this pressure 75 will have a tendency to straighten the spring and thereby increase its pressure against the under surface of the rail and the arm 17 so as to increase the pinching grip of the jaw 11 on the upper and lower surfaces of 80 the rail base. Any clearance that may exist between the edges of the rail base and vertical faces of the jaw 11, and abutment 15 will be taken up by a slight skewing action of the yoke when the rail is subjected to a creeping pressure. Under such conditions the yoke will take a firm shackle hold on the vertical edges of the rail base.

In Figs. 6 and 7 I have illustrated a modification in which the inner edge of the spring member 20^a extends into a recess 26 when it is in its applied position so as to prevent displacement of the spring member during a retrograde movement of the rail. The lower end of the arm 17^a of this 95 modification is also preferably formed with a recess 19^a adapted to receive the lower end of the spring member 20^a. In other respects the device shown in these figures may be the same in construction as that shown 100 in Figs. 1 to 5 inclusive.

In applying this device to a rail, the spring member 20^a, when arranged in the position shown in Fig. 2, stands, as indicated in dotted lines, beyond the end of the 105 lug 27 of Fig. 6 until the yoke is moved toward the tie to tension the spring. After the spring has been tensioned and positioned adjacent the tie, it may be driven transversely of the rail until its inner vertical edge enters the recess 26.

While I have described my invention in certain preferred embodiments, it will be obvious that other modifications might be made without departure from the spirit of 115 my invention. I therefore do not wish to be limited to the exact structures shown and described, except in so far as specific limitations may appear in the appended claims.

I claim:

1. A rail anchor comprising a yoke member adapted to bear against the under surface of a rail base and engaging opposite edges of said rail base, and a bendable key member cooperating with the yoke adapted 125 to hold the yoke in its operative position.

2. A rail anchor comprising a yoke member for engaging opposite edges of a rail base, and a key member cooperating with the yoke adapted, when in its applied position, 130

- to exert pressure on said yoke to rock the same on a horizontal axis.
3. A rail anchor comprising a yoke member for engaging opposite edges of a rail base, and a key member cooperating with the yoke adapted, when in its applied position, to exert pressure on said yoke to rock the same on a horizontal axis transversely of the rail.
- 10 4. A rail anchor comprising a yoke member for engaging opposite edges of a rail base, and a key cooperating with said yoke adapted, when in its applied position, to exert pressure on said yoke to rock the same on a horizontal axis extending transversely of the rail to effect a gripping contact of the yoke with the rail.
- 15 5. A rail anchor comprising a yoke member for engaging opposite edges of a rail base, and a key cooperating with said yoke adapted, when in its applied position, to exert pressure on said yoke to rock the same on a horizontal axis extending longitudinally of the rail, and thereby support the yoke in its operative position.
- 20 6. A rail anchor comprising a yoke member for engaging opposite edges of a rail base, and a key cooperating with said yoke adapted, when in its applied position, to exert pressure on said yoke, to rock the same on a horizontal axis extending transversely of the rail and on a horizontal axis extending longitudinally of the rail.
- 25 7. A rail anchor comprising a rail gripping member, and a spring key interposed between said member and the rail base adapted to rock said gripping member to effect a gripping contact of said member with the rail base.
- 30 8. A rail anchor comprising a rail gripping member, and a spring key interposed between said member and the rail base adapted to rock said member to effect a gripping contact of the same with the upper and
- 35 9. A rail anchor comprising a rail gripping member, and a spring key interposed between said member and the rail base adjacent one end of said member and adapted to rock said member to effect a gripping contact of said member with the rail base.
- 40 10. A rail anchor comprising a rail gripping member for engaging opposite edges of a rail base, and a spring key cooperating with said rail gripping member adapted, when in its applied position to rock said gripping member into gripping contact with the rail base and to provide a tie abutment.
- 45 11. A rail anchor comprising a yoke member for engaging opposite edges of a rail base, and a spring cooperating with said yoke adapted to exert pressure on the yoke to rock it into gripping contact with the rail base; said spring being arranged to provide a tie abutment whereby said spring pressure is increased when the rail is subjected to creeping pressure.
- 50 12. A rail anchor comprising a yoke member for engaging opposite edges of a rail base, and a spring cooperating with said yoke and strained in its operative position to exert pressure on the yoke to rock the same into gripping contact with the rail base; said spring being arranged to provide a tie abutment whereby said spring pressure is increased when the rail is subjected to creeping pressure.
- 55 13. A rail anchor comprising a yoke member for engaging opposite edges of a rail base, and a spring member adapted to be strained in its operative position to exert pressure on said yoke whereby the yoke is rocked into gripping contact with the rail; the spring being arranged to abut against a tie whereby it is subjected to further strain when the rail is moved longitudinally toward said tie.
- 60 14. A rail anchor comprising a yoke member for engaging opposite edges of a rail base, and a vertically disposed spring member positioned between said rail base and yoke member and adapted to be strained in its operative position to exert pressure on said yoke whereby the yoke is held in gripping contact with the rail; the spring being arranged to abut against a tie whereby it is subjected to further strain when the rail is moved longitudinally toward said tie.
- 65 15. A rail anchor comprising a yoke member for engaging opposite edges of a rail base, and a spring member interposed between the under-surface of the rail base and a portion of said yoke and adapted to be strained in its operative position; said spring being curved in vertical section and adapted to bear against a tie whereby movement of the rail toward said tie increases the grip of the anchor device on the rail.
- 70 16. A rail anchor comprising a yoke member for engaging opposite edges of a rail base, and a spring member interposed between the under-surface of said rail base and a portion of said yoke and adapted to be strained in its operative position; said spring being curved in vertical section and adapted to bear against a tie, whereby movement of the rail toward said tie tends to straighten said spring and thereby increases the grip of the anchor device on the rail.
- 75 17. A rail anchor comprising a yoke formed with a jaw portion to engage the upper and lower surfaces of one of the base flanges of a rail and with an abutment for engaging the vertical edge of the other base flange, and a key for supporting the abutment end of said yoke in operative position and adapted to bear against a tie.
- 80 18. A rail anchor comprising a yoke formed with a jaw portion to engage the upper and lower surfaces of one of the base flanges of a

- 5 rail and with an abutment for engaging the vertical edge of the other base flange, and a key member interposed between the under-surface of said rail and a portion of said 5 yoke and adjacent said jaw portion adapted to support the abutment end of said yoke in operative position and provide a tie abutting foot.
- 10 19. A rail anchor comprising a yoke formed with a hook-shaped jaw adapted to fit over one edge of a rail base and with an abutment for engaging the opposite edge of said base, and a spring interposed between said yoke and rail base and adapted to be 15 strained when the anchor is applied to the rail so as to exert pressure against said yoke to rock it into gripping engagement with the rail base.
- 20 20. A rail anchor comprising a yoke formed with a hook-shaped jaw adapted to fit over one edge of a rail base and with an abutment for engaging the opposite edge of said base, and a spring interposed between said yoke and rail base adjacent said jaw 25 and adapted to be strained when the anchor is applied to the rail, so as to exert pressure against said yoke.
- 30 21. A rail anchor comprising a yoke for engaging opposite edges of a rail, and a spring member cooperating therewith which is strained when the device is applied to a rail, whereby pressure is exerted on the yoke to support it against the under-surface of the rail base and to rock it into gripping 35 contact therewith.
- 40 22. A rail anchor comprising a yoke for engaging opposite edges of the rail, and a spring member cooperating therewith which is strained when the device is applied to a rail, whereby pressure is exerted on the yoke at one side of its longitudinal center to support it against the under-surface of the rail base and to rock it into gripping contact therewith.
- 45 23. A rail anchor comprising a yoke for engaging opposite edges of a rail base, and a vertically disposed spring member cooperating therewith which is strained when the device is applied to a rail, whereby pressure is exerted on the yoke at one side of its longitudinal center to support it against the under-surface of the rail base and to rock it into gripping contact therewith.
- 55 24. A rail anchor comprising a rail base embracing member formed with a depending flange, and a spring engaging said rail and said flange and adapted to exert pressure to rock said embracing member into gripping contact with the rail base; said 60 spring being positioned to abut against a tie when the device is in its applied position whereby said spring pressure is increased when the rail is subjected to creeping pressure.
- 65 25. A rail anchor comprising a yoke formed with jaws for engaging opposite edges of a rail base, and a spring member for supporting said yoke in gripping contact with the rail; the distance between said jaws being substantially the same as the width of 70 the rail base whereby the anchor, when in its applied position, stands at substantially right angles to the length of the rail.
- 75 26. A rail anchor comprising a yoke provided at one end with a hook shaped jaw adapted to fit over one edge of a rail base, a vertically disposed portion at the other end of the yoke providing an abutment for engaging the opposite edge of said base, a downwardly extending arm, and a spring 80 key member positioned to bear against the under-surface of said rail base and said arm and adapted to support said yoke in its rail gripping position; the distance between said jaw and said abutment being substantially 85 the same as the width of the rail base and the portion of the yoke defining the lower portion of said hook-shaped jaw being inclined downwardly, for the purpose described.
- 90 27. A rail anchor comprising a yoke formed at one end with a hook-shaped jaw adapted to fit over one edge of a rail base, a vertically disposed portion at the other end of the yoke providing an abutment for 95 engaging the opposite edge of said rail base, an arm adjacent said hook-shaped jaw extending downwardly toward a tie and formed with a spring supporting seat, and a spring adapted to be stressed between 100 said seat and the under surface of said base to bias said hooked-shaped jaw to grip the upper and lower surfaces of said base.
- 105 28. A rail anchor comprising a yoke provided at one end with a hook-shaped jaw adapted to fit over one edge of a rail base, a vertically disposed portion at the other end of the yoke providing an abutment for 110 engaging the opposite edge of said base, an arm adjacent said hook-shaped jaw extending downwardly toward a tie and formed with a spring supporting seat, and a spring adapted to be stressed between said seat and the under surface of said rail base to bias 115 said hook-shaped jaw to grip the upper and lower surfaces of said rail base; the distance between said jaw and said abutment being substantially the same as the width of the rail base and the portion of the yoke defining the lower portion of said hook-shaped jaw being inclined downwardly, for the purpose described.
- 120 29. A rail anchor comprising a yoke member provided at one end with a hook-shaped jaw adapted to fit over one edge of 125 a rail base, a vertically disposed portion at the other end of the yoke providing an abutment for engaging the opposite edge of said rail base, an arm adjacent said hook-shaped jaw extending downwardly toward 130

a tie and formed with a spring supporting seat, and a spring adapted to be stressed between said seat and the under-surface of said base to bias said hook-shaped jaw to grip the upper and lower surfaces of said base; said spring member being positioned to abut against a tie adjacent one end of said yoke whereby the jaw and said vertically disposed portion of said yoke grip the opposite edges of the rail base with a shackle hold when the rail is moved longitudinally.

30. A rail anchor comprising a rail base engaging yoke formed with a depending arm provided at its lower end with a recess, and a spring adapted to be seated in said recess and stressed to bear against the under-surface of said rail base.

31. A rail anchor comprising a rail base engaging yoke formed along its edge with a recess and provided with a depending arm, and a spring interposed between said arm and said rail base and adapted to be driven transversely of the rail into said recess.

32. A rail anchor comprising a rail base engaging yoke formed along its edge with a recess and provided with a depending arm, and a spring stressed in a position between said arm and said rail base and adapted to be driven transversely of the rail into said recess.

33. A rail anchor comprising a yoke provided at one end with a hook-shaped jaw adapted to fit over one edge of a rail base, a vertically disposed portion at the other end of the yoke providing an abutment for engaging the other edge of said rail base, an arm adjacent said hook-shaped jaw formed with a spring seat and extending downwardly toward a tie to provide one part of a tie abutment, and a curved spring cooper-

ating with said arm to provide the other part of said tie abutment; said curved spring being normally of greater length, when free of the rail, than the distance between said rail base and said seat portion, whereby the application of said spring to its operative position subjects it to a bending strain.

34. A rail anchor comprising a yoke provided at one end with a jaw adapted to fit over one edge of a rail base, a vertically disposed portion at the other end of said yoke providing an abutment for engaging the other edge of said base, an arm adjacent said hook-shaped jaw formed with a spring seat and extending downwardly toward a tie to provide one part of a tie abutment, and a spring curved in a vertical plane cooperating with said arm to provide the other part of said tie abutment, said curved spring being normally of greater length, when free of the rail, than the distance between said base and said seat and is formed with an inclined edge extending downwardly toward the center of the rail, for the purpose described.

35. A rail anchor comprising a rail base embracing yoke and a bowed spring member arranged substantially vertically between the rail base and said yoke and adapted to flex on a line transversely of the rail.

36. A rail anchor comprising a rail base embracing yoke and a substantially vertically arranged spring between the rail base and said yoke to produce a grip of the yoke on said base; said spring being arranged to bear at one end against the rail base and at the other end against the yoke.

LAURENCE J. BERKELEY.
